United States Patent Office

Des. 179,018
Patented Oct. 23, 1956

179,018

SHOP HAMMER

Robert A. Lowe, Cleveland Heights, and Frank F. White,
Shaker Heights, Ohio

Application December 29, 1954, Serial No. 33,732

Term of patent 14 years

(Cl. D93—4)

Fig. 1

Fig. 2

Fig. 3

Fig. 1 is a front elevation of a shop hammer showing our design;

Fig. 2 is a side elevation of the hammer; and

Fig. 3 is an enlarged cross-sectional view taken along line 3-3 of Fig. 1.

We claim:

The ornamental design for a shop hammer, as shown.
